INTERNATIONAL CHRONOMETER

Arthur M. Braaten, Riverhead, N. Y., assignor to
 Radio Corporation of America, a corporation of
 Delaware

Application February 23, 1938, Serial No. 191,864

9 Claims. (CL. 58—43)

This invention relates to the art of reckoning time and deals more specifically with a chronometer or international time clock which gives the standard time in any part of the world. The dial and the mechanism of the clock are so arranged as to show directly standard time and Greenwich mean time in any part of the world, and also the local time of the place at which the clock is located.

An object of this invention is to simplify and improve chronometers, so that in addition to the local time, a direct reading of standard time and Greenwich mean time in any part of the world may be readily obtained.

Another object of this invention is to provide an improved chronometer with a twenty-four hour movement and to associate therewith a rotating geographical scale and a rotatable scale indicating Greenwich mean time.

Because of the rotation of the earth on its axis from west to east, sunrise takes place at any given point earlier than at a place to the west of that point. This means that all places east of a given meridian are ahead in time, while those west are behind. Since the earth makes one complete rotation in twenty-four hours, it takes exactly one hour for the sun to make a transit across the space between the meridians of two places separated by fifteen degrees in longitude. By international agreement, the world has been divided into time zones, each fifteen degrees of longitude in width. The time in each zone is the same as that of the meridian passing through its center, and the times in adjacent zones differ by one hour. All time is reckoned from the prime meridian of Greenwich, the time on that meridian being termed Greenwich mean time, or G. M. T. Most of the countries of the world follow the international time system, but a few use the local time of some important city.

Heretofore, in order to determine the time at any place in relation to the time at any other place, it has been necessary to consult tables or make use of conversion charts. This procedure is both inconvenient and unsatisfactory, because of the time required in making the conversions and the great possibility of making errors. Since it is desirable to be able to determine accurately the time in any part of the world with the least amount of effort, the present invention was brought forth to give this time directly from the dial, thus doing away with the necessity of using tables and conversion charts. It is therefore an object of this invention to provide a more ac-

curate and useful means of determining the time in any part of the world.

The present invention may best be described by reference to the accompanying drawings, which shows one specific embodiment of the same.

Referring now to the drawings, Fig. 1 is a front elevation showing the chronometer face;

Fig. 2 is a section taken on line 2—2 of Fig. 1;

Fig. 3 is a partial front elevation showing another embodiment;

Fig. 4 is a partial section of Fig. 3;

Fig. 5 is a partial section of a further embodiment;

Fig. 6 is a detail section showing a modification of Figs. 4 and 5; and

Fig. 7 is a detail section showing another modification of Figs. 4 and 5.

Referring now to Figs. 1 and 2 of the drawings, 1 is a stationary, twenty-four hour time dial and is to be used in connection with a timepiece having a twenty-four hour movement. This dial is suitably marked to indicate the hours 1 to 12 a. m. and also 1 to 12 p. m. Extending over to the face of dial 1 are hour hand 4 and minute hand 5. The latter hand extends slightly beyond the hour hand. Both hands are operated by any suitable time clock mechanism 6. Hands 4 and 5 are arranged to indicate on dial 1 the local time at any place at which the timepiece is to be used. Located within dial 1 is a ring-like disc or annulus 2 which may be rotated about an axis passing through its center, by any suitable manual means, such as for example, a finger engaging

35 depressed portion 7. Ring 2 is marked to show Greenwich mean time and is arranged so that it can be manually set to show the G. M. T. corresponding to the local time at any given place. Within the center of the chronometer there is 40 located a movable disc 3 which normally travels with hour hand 4 and is equipped with a disc-like clamp or friction clutch 8 which, by means of a plurality of spring members 9, applies through a plurality of fingers 10 friction, so as to engage the underside of dial 3. The lower end of fingers 10 are retained in place by means of nuts 11. A depressed finger engaging portion 1a is provided preferably on the outside of dial 3, so as to allow its being set manually in any 45 desired position with respect to hour hand 4. The face of dial 3 is laid out in sections corresponding to the international time zones, each section covering fifteen degrees of longitude. In the center of the disc 3, sections are marked in 50 the degrees longitude, east and west of Green-

wich, of the meridians of the time zones. In each section are indicated the principal country, or countries, of the corresponding time zone. Since some countries use a time which differs from standard time by one-half hour, these countries are indicated on the movable disc 3 as being small sections formed from an equal portion of each of two adjacent standard time hour sections. For protection against dust, moisture, etc., the entire mechanism is preferably enclosed within in a suitable casing 12 with a glass face 13.

The embodiment shown by Figs. 3 and 4 is in general similar to Figs. 1 and 2, except that dial 3 is positively secured to the hour hand 4 by means of a threaded pin 14 and washer 15, the dial 3 having located on its surface twenty-four holes equally spaced in the center of each hour section to receive pin 14. This arrangement does away with the friction drive or clutch 8 and its associated elements 9, 10, 11. Ring 2 is supported by means of a plurality of equally spaced posts 16 which support a track 17. The underside of ring 2 has spring clips 18 that grip in frictional engagement track 17, ring 1 being fixed to the casing 12b by any suitable means.

The other embodiment shown by Fig. 5 is similar to Fig. 4, except that the rings 1 and 2 are reversed in position, that is, ring 2a is outside and ring 1a inside, a plurality of spacers 20 and 21 securing ring 1a to case 12a by means of screws 22 and 23. Post 16a is supported by a strip 24.

The modifications to the dials shown by Figs. 6 and 7 comprise a one piece disc 25 pivoted to the hub of clock mechanism 6 to which a ring-like dial 2b is secured for rotation and retained by any suitable means, such as a lip 26, cut and bent over from the metal of disc 25. The outer rim portion of disc 25 and dial 2b is marked and functions similar to members 1 and 2, respectively, of Fig. 1. Fig. 7 shows a ring-like dial 2c located at the outside rim portion of a member 25a and secured thereto by a screw 27. The dial 25a is provided with twenty-four holes located in the center of each hour section for securing dial 2c and member 25a in a desired position. Just within the inside diameter of ring-like dial 2c, disc 25a has a step-like raised portion to provide a dial surface which will lie in the same plane as the surface of dial 2c. The raised portion 28 of member 25a and ring-like dial 2c is marked and functions similar to members 1 and 2, respectively, of Fig. 1.

The operation of the device is as follows:

The clock is first set so as to indicate on dial 1 the local time of the place at which it is to be used. Then disc 2 is turned until the hands also indicate the G. M. T. of said place, at which setting it is allowed to remain. Now, disc 3 is rotated until the time zone corresponding to the location of the clock is opposite the local time reading. It is then maintained at this setting and travels with the hour hand. The clock will now correctly indicate the following: local time of the place at which it is located, the G. M. T. corresponding to this local time (which is, of course, the same for the whole world), and the standard time of any country using standard time. The extreme usefulness of such a device will be readily apparent.

The drawing, as shown by Fig. 1, has been laid out to show how the clock dial would be set for any location using Eastern Standard Time. When it is 6:00 a. m. in New York, the corresponding G. M. T. is 11:00, the G. M. T. of course

being the same all over the world. At the same time it is 1:00 a. m. in Alaska, noon in middle Europe, 4:30 p. m. in India, 8:00 p. m. in Japan, 8:30 p. m. in central Australia, and 10:30 p. m. in New Zealand. While it is 11:30 p. m. of a certain day in British Samoa, it is 10:30 p. m. of the new day in New Zealand as the international date line is situated between these two countries. This is because Samoa lies between the 180th meridian and midnight on the clock dial. In crossing the 180th meridian, the international date line, from east longitude to west longitude, a day is lost; in crossing from the opposite direction, a day is gained. When the midnight line is passed by the pointer on the dial, there is, of course, also a change in the date. In going around the dial clockwise, it is one date from the 180th meridian to midnight, and another date, or the following day, for the rest of the way around the dial.

Furthermore, in Fig. 1 of the drawings, only one-hour divisions are shown on disc 1. It should be understood, however, that divisions of one minute could be used on the dial. Of course, on a larger disc 3, more countries could be indicated in the various zones. Countries differing from standard time could be indicated thus "Algeria, -9 minutes." If it were desired to indicate only the more important countries in the various zones, the clock could be arranged to indicate the time in all countries as follows. The Hydrographic Office of the United States Navy publishes a map showing the time zones in colors. All countries in the same zone using standard time are uniform in color. Those countries using local time are colored differently and the amount of departure from standard time is indicated with the name of the country. The various sections on disc 3 of the present invention could be colored to correspond to the time zones on the map which they represent. It can be seen that this would make an exceedingly useful arrangement.

While only one embodiment of this invention has been described, it is to be distinctly understood that it will not be limited to the type shown, but should only be limited to such limitations as are clearly imposed in the appended claims.

What is claimed is:

1. A chronometer adapted to indicate the standard time and Greenwich mean time of different locations on the earth, comprising a stationary dial, said stationary dial having a scale thereon with numerals representative of local time, a minute hand, an hour hand, a twenty-four hour time-piece mechanism having means to rotate said minute hand and said hour hand, a movable dial having a scale which is divided in sections of fifteen degrees and having located within said sections the principal geographical location, or locations, to which the said section corresponds, means coupled to said mechanism to rotate said movable dial, and a third dial having indications corresponding to Greenwich mean time located thereon, a casing for said chronometer, a track secured within said casing with means to move said third dial, said third dial arranged to move on said track so as to be rotated with respect to said stationary dial, said hour and minute hands extending over said rotatable and third dials to indicate a desired time on said stationary dial.
2. A chronometer adapted to indicate the standard and Greenwich mean time of different

locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to the local time on said stationary dial, a third dial concentric with said stationary and movable dials, said third dial having a scale thereon with names representative of different geographical locations, a plurality of pointers, and a rotating mechanism having means to rotate said plurality of pointers and said third dial, said pointers extending over said movable and third dials to indicate a desired time on said stationary dial.

3. A chronometer adapted to indicate the standard and Greenwich mean time of different locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to local time on said stationary dial, a third dial concentric with said stationary and movable dials, said third dial having a scale thereon with names representative of different geographical locations, an hour hand, a minute hand, indicating mechanism having means to rotate said hour and minute hands and said third dial, said hour and minute hands extending over said movable and third dials to indicate a desired time on said stationary dial.

4. A chronometer adapted to indicate the standard and Greenwich mean time of different locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to the local time on said stationary dial, a third dial concentric with said stationary and movable dials, said third dial having a scale thereon with names representative of different geographical locations, an hour hand, a minute hand, indicating mechanism having means to rotate said hour and minute hands and said third dial, a friction clutch located between said hour hand and said third dial to normally simultaneously rotate said third dial with said hour hand, said hour and minute hands extending over said movable and third dials to indicate a desired time on said stationary dial.

5. A chronometer adapted to indicate the standard and Greenwich mean time of different locations on the earth comprising a stationary dial having a twenty-four hour scale thereon with numerals representative of local time, a movable dial concentric with said stationary dial, said movable dial having a scale thereon with numerals representative of Greenwich mean time, said movable dial having means whereby it may be manually set to show the Greenwich mean time corresponding to the local time on said stationary dial, a third dial concentric with said stationary and movable dials, said third dial having a scale thereon with names representative of different geographical locations, an hour hand, a

minute hand, twenty-four hour indicating mechanism having means to rotate said hour and minute hands and said third dial, a friction clutch located between said hour hand and said third dial to normally simultaneously rotate said third dial with said hour hand, said hour and minute hands extending over said movable and third dials to indicate a desired time on said stationary dial.

10 6. A chronometer adapted to indicate the standard and Greenwich mean time of different locations on the earth comprising a stationary dial having a twenty-four hour scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to the local time on said stationary dial, a third dial concentric with said stationary and movable dials, said third dial having a scale thereon dividing it into sections of fifteen degrees, each section having located therein a name representative of a different geographical location, a plurality of pointers, and a rotating mechanism having means to rotate said plurality of pointers and said third dial, said pointers extending over said movable and third dials to indicate a desired time on said stationary dial.

20 7. A chronometer adapted to indicate the standard and Greenwich mean time of different locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to the local time on said stationary dial, a third dial concentric with said stationary and movable dials, said third dial having a depressed finger portion so that it may be manually moved with respect to said stationary dial, said third dial having a scale thereon with names representative of different geographical locations, a plurality of pointers, and a rotating mechanism having means to rotate said plurality of pointers and said third dial, said pointers extending over said movable and third dials to indicate a desired time on said stationary dial.

25 8. A chronometer adapted to indicate the standard and Greenwich mean time of different locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to the local time on said stationary dial, a third dial concentric with said stationary and movable dials, said third dial having a scale thereon with names representative of different geographical locations, an hour hand, a minute hand, indicating mechanism having means to rotate said hour and minute hands and said third dial, a friction clutch having a plurality of spring members, said spring members located between said hour hand and said third dial to normally simultaneously rotate said third dial with said

hour hand, said hour and minute hands extending over said movable and third dials to indicate a desired time on said stationary dial.

9. A chronometer adapted to indicate the standard and Greenwich mean time of different locations on the earth comprising a stationary dial having a scale thereon with numerals representative of local time, a movable dial concentric with said stationary dial, said movable dial having a scale thereon with numerals representative of the Greenwich mean time, said movable dial having means whereby it may be manually set to show the Greenwich mean time corresponding to local time on said stationary dial, a third dial

concentric with said stationary and movable dials, said third dial having a plurality of apertures therein and a scale thereon with names representative of different geographical locations, an hour hand, a minute hand, indicating mechanism having means to rotate said hour and minute hands and said third dial, a pin member engaging one of said apertures and said hour hand to simultaneously rotate said third dial with said hour hand, said hour and minute hands extending over said movable and third dials to indicate a desired time on said stationary dial.

ARTHUR M. BRAATEN.
